UNITED STATES PATENT OFFICE.

ARTHUR C. ROWLEY, OF PHILADELPHIA, PENNSYLVANIA, ASSIGNOR TO GLOBE AUTOMATIC SPRINKLER COMPANY, OF PHILADELPHIA, PENNSYLVANIA, A CORPORATION OF PENNSYLVANIA.

FUSIBLE LINK.

Application filed May 27, 1922. Serial No. 564,260.

One object of this invention is to provide a novel form of temperature-responsive link particularly designed for use in connecting the movable parts of automatic sprinklers or 5 normally holding together the two parts of a chain or rope so that these shall be automatically disconnected when the link is subjected to predetermined abnormal temperature.

10 The invention further contemplates a simple, structurally strong form of fusible link including two interchangeable elements of identical construction particularly designed to sustain for long periods of time a predetermined tensile stress, without likelihood 15 of their slippage or separation while at the same time being free to permit such separation to occur whenever the temperature in their vicinity rises to a predetermined 20 point.

I further desire to provide a fusible link of the above noted type with elements whose cooperating faces include portions of novel form particularly designed to impart to the 25 assembled link the above noted desirable characteristics while facilitating the separation of the parts of said link when the fusible metal normally connecting them shall have been sufficiently softened or fused.

30 These objects and other advantageous ends I attain as hereinafter set forth, reference being had to the accompanying drawings, in which,

Fig. 1 is a plan of a fusible link constructed in accordance with my invention;

Fig. 2 is a longitudinal vertical section on the line 2—2, Fig. 1;

40 Figs. 3 and 4 are fragmentary elevations of the cooperating parts of the two link elements;

Fig. 5 is an end elevation of the structure shown in Fig. 3;

45 Figs. 6 and 7 are vertical sections on the lines 6—6 and 7—7 of Figs. 3 and 4 respectively; and

Fig. 8 is a plan of a slightly modified form of fusible link.

In the above drawings 1—1 represent a pair of generally flat, elongated metallic plates, each of which has one end of more or less circular outline and provided with a perforation 2. By suitable means the edges of this perforation, which is preferably circular, are thickened to form annular 50 ribs 3 projecting from both plane faces of

the element. Beyond this eyelet each plate is laterally flared to a maximum width and is thereafter contracted to a width substantially that which it has adjacent said eye. The end of the element distant from said eye is formed with a pair of pressed out 60 projections 4 designed to engage the plane face of the other element so that said two elements will be spaced a definite distance apart so as to receive the solder or other 65 relatively fusible metal whereby said elements are normally connected.

At substantially the middle of that end of each link distant from the opening 2, the metal of each plate is displaced so as to 70 form in one face thereof an elongated depression extending in the central longitudinal line and the opposite face of the plate is correspondingly bulged or forced out so that there is formed a longitudinally extending projection 5 substantially U-shaped in cross section. In the body of each plate adjacent its perforation 2, and like the projection 5, disposed symmetrically with regard to its longitudinal center line, there is 75 formed an opening 6 having two parallel sides and formed with its end adjacent the perforation 2 at right angles to said sides. Its second end is preferably given a semi-circular curvature and is formed with a 80 curved lip 7 extending from its otherwise plane surface on that side thereof opposite the projection 5.

The dimensions of this opening 6 and the form of the inner surface of the lip 7 are 85 such that the projection 5 of a second identically formed plate will more or less snugly fit into and cooperate therewith when the two plates are superposed, as shown in Figs. 1 and 2, the projection 5 of each plate extending into the opening 6 of the other plate and the body portions of the two plates lying parallel with each other, as shown in the drawings, but spaced apart a predetermined distance dependent upon the dimensions of the projections 4.

100 Each of the projections 5 of one plate is so curved or formed as to conform to the curvature of the lip 7 of the other plate so that when the two plates are connected by 105 solder or other relatively fusible metal, any tensile stress which may be applied by suitable elements inserted in the openings 2 is for the most part transmitted from one plate to the other through their lips 7 and coact- 110

THOMAS NATHAN RUSSELL, OF CHICAGO, ILLINOIS, ASSIGNOR, BY MESNE ASSIGNMENTS, TO CHICAGO-CLEVELAND CAR ROOFING COMPANY, OF CHICAGO, ILLINOIS, A CORPORATION OF DELAWARE.

UNCOUPLING DEVICE FOR COUPLINGS. **BEST AVAILABLE COPY**

Application filed November 14, 1922. Serial No. 600,834.

This invention relates broadly to railway rolling stock appliances and more particularly to improvements in uncoupling devices for car-couplers.

5 This invention is primarily intended as an improved and simplified attachment for the purpose of lifting or otherwise moving the lock-pin or other member usually employed for maintaining an automatic or other railway car-coupler closed, and while the present invention finds especial usefulness in this employment, and is so illustrated for convenience, it will be readily understood that it finds a wide field of utility for other purposes.

The principal objects and advantages which characterize this invention reside in the provision of improved means for releasing or uncoupling a railway car-coupler, especially those of the automatic type, the provision of improved means for releasing a railway car-coupler, which means may be operated by the hand or foot of the trainman while riding a car; the provision of an improved lever arrangement for lifting the locking pin of and thus opening a railway car-coupler; the provision of improved means operable either by the hand or foot for lifting the locking pin of and thus opening a railway car-coupler; the provision of improved means for lifting the locking pin of and releasing a railway car-coupler which is characterized by the association therewith of means for preventing the operator from moving the device too far and to prevent the operator from being struck by parts in the event of their fracture; and the provision of a device of the character described which generally improves and simplifies railway coupling release apparatus and increases the degree of safety with which they may be operated.

It is further an object of this invention to provide means for releasing or opening a railway car-coupler which is standard and may be conveniently applied to any railway car without interference with or material alteration of existing parts of the car construction; and wherein the required displacement vertically laterally and longitudinally of the coupler in use is accommodated.

Other and more specific objects and features of this invention will appear or be pointed out as this description proceeds, one

embodiment of this invention being illustrated in the accompanying drawing, wherein:

Figure 1 is an end elevational view of a railway car and coupler equipped with a device constructed in accordance with the present invention;

Figure 2 is a plan view of the same.

Referring more particularly to the drawing, there is illustrated in fragmentary elevation the end sill 5 of a standard railway car, which, as here shown, may be that of either a gondola or box car. At the center of the sill an automatic coupler 6 of a conventional construction is mounted and from said coupler there extends a locking pin 7, having an eye 8. The brake staff is shown at 9, mounted in a bracket 10, and a hand rail 11 is also provided for the convenience of the trainman. Another hand rail 11^a is provided on the corner post of the car.

It is well known to those skilled in the art that in shunting freight cars, and in fact other railway rolling stock in a classification yard, or on sidings or in a terminal, it is customary for the trainman or switchman to ride the end of a car next to that car or series of cars which it is desired to shunt into a siding and at the proper instant to release the coupler and permit such cars to proceed by their momentum from the rest of the train. Under the most ideal conditions this is a hazardous occupation as the conventional form of coupler releasing means generally employed requires that the trainman must use one hand to grasp a hand rail on the end of the car and with the other hand release the coupler. In the present invention I provide means in which the switchman or trainman may occupy a safe position, may use one or both his hands to sustain himself and safely employ his foot for releasing the coupler. As most of the automatic couplers employ a locking pin, which, for releasing the coupler, is lifted, I have shown my invention as employed for lifting such pin.

Referring first to Fig. 1 I provide a bracket 12, which latter is riveted or otherwise fixedly secured to the face of the end sill 5, said bracket having a fulcrum bearing member 13, provided with a base portion 14 fixedly secured to the bracket 12 by the provision of rivets 15-15. A fulcrum
